WALTER M. DANN, OF WILKINSBURG, PENNSYLVANIA, ASSIGNOR TO WESTINGHOUSE ELECTRIC & MANUFACTURING COMPANY, A CORPORATION OF PENNSYLVANIA.

RADIATOR.

Application filed January 8, 1921. Serial No. 435,953.

My invention relates to heat-dissipating devices and it has particular relation to apparatus of the above-designated character adapted to be utilized in connection with electrical or other apparatus normally immersed within a cooling fluid.

More specifically, my invention relates to means for cooling the oil or other cooling fluid that is employed in transformers or to other structures in which it is desired to embody oil-tight air-cooled radiators.

The object of my invention is to provide a radiator wherein the air, or other cooling medium, may have a free and unobstructed passage between the various radiator units or sections.

Another object of my invention is to provide a radiator, of the character described, having a relatively large area of cooling surface, in comparison with the space occupied thereby.

A further object is to provide a device of the character described that may be quickly and easily constructed from suitably formed sheet-metal elements and one that will be of strong and rugged construction.

Heretofore, in structures of this general character, the radiator units were either arranged separately around the perimeter of a transformer tank or they were arranged collectively in groups upon the tank, each group being provided with a common connection which communicates with the tank.

In the former of these structures, the sides of the tank were necessarily provided with a large number of spaced apertures arranged in rows and with which the respective radiator units communicated. In such structure, each of the radiators required several connecting or coupling members which were separately attached to the side of a transformer tank.

It was, therefore, necessary to so space the various radiator units from each other as to render the coupling members easily accessible in assembling or disassembling the apparatus. By thus spacing the radiators, there was not only considerable valuable unoccupied space which was greater than was necessary to furnish the required circulation of air between the units, but only a limited and insufficient number of radiators could be so mounted upon a tank.

In the latter of the two general methods of

arranging the radiator units, the radiators were grouped to communicate with upper and lower apertures in the walls of the tank by means of common header members arranged at the upper and lower extremities of the several groups of units. The header members, while generally simplifying the radiator structure by reducing the number of apertures required in the tank and the coacting coupling members, were located directly above and below the units of each group and materially interfered with the vertical circulation of the air between the same.

Moreover, in both of these general structures, the units of the respective radiators were not braced against lateral pressure, and frequently became displaced thereby causing leaks to develop.

According to my invention, I provide a radiator comprising a plurality of separate units which communicate with upper and lower header members so arranged at one side of the group of units as not to interfere with the circulation of air therebetween.

Furthermore, in my structure, the various parts are preferably constructed of previously formed sheet metal which are welded together to constitute a comparatively light but strong and rugged structure the component parts of which are adequately braced against lateral pressure.

In the accompanying drawing,

Fig. 1 is a front elevational view of a radiator constructed in accordance with my invention.

Fig. 2 is a top plan view of the structure shown in Fig. 1.

Fig. 3 is an end elevational view of the structure shown in Figs. 1 and 2, the central portions of the radiator units being broken away.

Fig. 4 is a fragmentary vertical sectional view, on a large scale, on line IV-IV of Fig. 2, and which illustrates the method of welding the radiator units to the offset header members.

Referring to the drawings, a radiator is shown as comprising a plurality of relatively flat rectangular units or cells 1 which are vertically arranged in spaced and parallel relation with respect to each other. The units 1 are preferably formed of a plurality of relatively flat complementary dish-shape members or side walls 2 provided with flanges 3

which extend around the perimeters thereof. The members 2 are also provided with depressed projections or channel portions 4 adjacent to each of the ends thereof.

5 When a plurality of the members 2 are arranged in side-by-side relation and their flanges 3 welded, or otherwise suitably secured together, they constitute a relatively wide and flat envelop having upper and lower tubular projections 5 extending in the same direction therefrom.

Upper and lower header members 6 are of boxlike structure and their various parts are also preferably formed of sheet metal and 15 welded together. The lower portions of the front walls 7 of the header members 6 are preferably inclined inwardly, as indicated at 8, and are provided with a plurality of spaced apertures 9 in which the tubular ext- 20 tensions 5 of the units 1 are adapted to be secured, preferably by welding, as indicated at 10. The purpose of disposing the wall 8 at an angle to the vertical is to aid the circulation of the cooling medium therethrough. 25 This is effected by reason of the fact that the cooling medium, in passing from the tubular member 4 and the header member 6, need not pass through a 90° angle.

The various units 1 of the radiator thus 30 project outwardly from the header members 6 and may be bound together by means of upper and lower transversely extending bolts 11 and spacing members 12. The side walls 2 of the units 1 may also be provided with 35 longitudinal corrugations or depressions 13 which perform the double function of both stiffening or reinforcing the members and directing the vertical flow of oil or other cooling medium through the units.

40 The upper and lower header members 5 are preferably provided with centrally disposed enlargements or extrusions 14 the rear walls of which are each provided with an aperture 15 in which a suitable coupling 45 member 16 is adapted to be welded, as indicated at 17. The coupling member 16 is preferably provided with oppositely extending ear members 18 which are secured to the side wall of the transformer tank by means of 50 bolts 19.

By this construction, it will be apparent 55 that the air may circulate vertically between the respective units of the radiator and over the entire surfaces thereof. The respective header members are thus so offset as to eliminate the dead-air spaces that have heretofore

occurred in the vicinity of the upper and lower extremities of the radiator units.

I claim as my invention:

1. A radiator comprising a plurality of 60 cooling elements each comprising a pair of complementary sections provided with outwardly extending channel portions, said channel portions being adapted to form tubular projections when said sections are secured together, and a plurality of header members communicating with said projections and offset with respect to said cooling elements, whereby said header members are substantially without the area of vertical projection of said cooling elements.

2. A radiator comprising a plurality of 65 cooling elements, each of said elements comprising a pair of complementary sections provided with outwardly extending channel portions, said channel portions being adapted to form tubular projections when said sections are secured together, and a plurality of header members communicating with said projections and arranged at the side of said cooling elements, in such manner that the flow of air vertically therebetween is substantially unobstructed.

3. A radiator comprising a group of 70 relatively flat cooling units arranged in spaced relation with respect to each other, each of said units comprising a pair of complementary sections provided with outwardly extending channel portions, said channel portions being adapted to form tubular projections when said sections are secured together, and a plurality of header members communicating therewith and offset with respect to said cooling units, whereby said header members are without the normal vertical path of 75 air flowing between said cooling units.

4. A radiator comprising a plurality of 80 cooling units, each comprising a plurality of complementary sections of substantially 85 dish shape provided with outwardly extending channel portions adapted to co-operate with each other to form tubular projections when said sections are secured together, and a plurality of box-like header members arranged adjacent to the ends of said units, but substantially without the area of vertical projection of said units and communicating with said tubular projections.

In testimony whereof, I have hereunto subscribed my name this 5th day of January, 1921.

WALTER M. DANN.
